(57) **CLAIM**

The ornamental design for a “bottle shipping top cap insert,” as shown and described.

DESCRIPTION

FIG. 1 is a perspective view of the top, front and right sides of a bottle shipping top cap insert shown in a typical use configuration;

FIG. 2 is a front elevation view of the bottle shipping top cap insert;

FIG. 3 is a right side elevation view of the bottle shipping top cap insert;

FIG. 4 is a rear elevation view of the bottle shipping top cap insert;

FIG. 5 is a left side elevation view of the bottle shipping top cap insert;

FIG. 6 is a top plan view of the bottle shipping top cap insert;

FIG. 7 is a bottom plan view of the bottle shipping top cap insert;

FIG. 8 is a perspective view of a bottle shipping top cap insert for assembly with a bottle shipping package; and,

FIG. 9 is a cutaway view of the package of FIG. 8 incorporating the bottle shipping top cap insert.

The broken-lines of FIGS. 7 through 9 depict elements of the environment. These broken line features are depicted for illustrative purposes only, and form no part of the claimed design.
